George E. Phelan

UNITED STATES PATENT OFFICE.

GEORGE E. PHELAN, OF NEW YORK, N. Y.

IMPROVEMENT IN BILLIARD-TABLE CUSHIONS.

Specification forming part of Letters Patent No. **136,178**, dated February 25, 1873.

To all whom it may concern:

Be it known that I, GEORGE E. PHELAN, of the city, county, and State of New York, have invented a new and useful Improvement in Cushions for Billiard-Tables; and I do hereby declare the following to be a true, full, and correct description of the construction and operation of the same, reference being had to the accompanying drawing making part and parcel of this my specification.

The nature and object of my invention is to make and construct a cushion to be applied to billiard-tables that shall possess all the necessary elasticity required; at the same time, also, a durability not obtained by the cushions now in use.

In order to enable others skilled in the art to make and use my invention, I will proceed to describe the same in its mode of construction and operation.

Figure 1 represents a portion of a billiard-table, showing the bed of the same A, the side B screwed to the bed, and the position of the cushion C, fastened to its bed D by either screws or wire, or any other obvious and convenient manner. The cushion C is a metallic spring, of what is called a **U** or **V** shape, running around the whole of the length and width of the billiard-table; constructed preferably of the most elastic metallic material, the outer side of which being covered with the usual cloth lining; the upper and inner end of the spring, against which the billiard-balls impinge in their movements around the table, is left free and unattached to any portion of the frame-work of the table, and is of such a sensitive and elastic nature as to receive without injury the balls that may be forced against it, giving great activity to the rebound, and causing a much greater length of cushion being brought into action than by the usual mode of construction. If under certain circumstances a greater amount of elastic power is desired to be given to the billiard-cushion, I can also apply the same by constructing an India-rubber spring or bed, F, conforming to the shape of the **U** or **V** shaped metallic spring, and into which such spring may be placed and adjusted in the manner shown in Figs. 2 and 3,

and the whole attached to the spring or cushion-plate in any convenient manner, the India-rubber spring or bed F being of the same length of the metallic **U** or **V** shaped springs, into which they may be placed.

In the drawing, Fig. 1 is a perspective view of a portion of a billiard-table, showing the subject-matter of my invention as applied to the same. Fig. 2 is a cross-section of the same in the **U**-shaped form; Fig. 3, a cross-section in the **V**-shaped form, both of the latter figures showing the metallic spring surrounded by the spring or bed made of India rubber.

In this drawing, A represents the bed of the table; B, a portion of the frame-work screwed to the bed, to which is attached the billiard-cushions in the usual manner. C is a metallic spring or cushion, surrounding the whole table, and adjusted to the wooden cushion bed-plate D. F is the India-rubber spring or bed, surrounding the metallic spring C, both of which are of the same shape, configuration, and length. G is the table-cloth, covering the bed and cushions, adjusted in the usual manner; and H, the billiard-ball in contact with the cushion or spring. The metallic spring or cushion can be used independently of the rubber spring or bed, which mode of application I prefer, but may adopt both in practice when desired.

What I claim as my invention, and desire to secure by Letters Patent, is—

1. The **U** or **V** shaped metallic spring or cushion C for billiard-tables, formed in one piece and applied directly to the bed of the cushion, in the manner and for the purpose herein set forth.

2. The combination of the metallic spring or cushion C, formed in one piece, with the India-rubber spring or bed surrounding the same, also formed in one piece, both being of **U** or **V** shape, and applied directly to the billiard-table, in the manner and for the purpose herein set forth.

GEORGE E. PHELAN.
